SHEET HOLDER

Bruce K. Slonneger, Dayton, Ohio, assignor to
 The National Cash Register Company, Dayton,
 Ohio, a corporation of Maryland

Application February 23, 1949, Serial No. 77,936

5 Claims. (Cl. 281—44)

1

This invention relates to sheet holders adapted to releasably hold a plurality of sheets.

The invention is illustrated as adapted for use in restaurants, and as illustrated, consists of a holder for guest tickets, which holder is clipped to, or secured to, the counter top, or table, in a position convenient opposite a guest where the waitress can enter the order. The holder has a compartment adapted to receive a pile of guest tickets which are removably held therein, and the compartment is provided with a sliding closure which is movable under a removed guest ticket to provide a writing table therefor.

An object of the invention is to provide a convenient holder for restaurant guest tickets which are made readily available to a waitress for marking items of food wanted.

Another object of the invention is to provide a holder for restaurant guest tickets removably mounted on the counter or table in front of guests to be served.

Another object of the invention is to provide a resilient clamp to maintain the holder in position on a counter top or table.

A specific object of the invention is to provide a convenient holder for a pile of restaurant tickets which completely encloses the pile to protect them against becoming soiled, or otherwise mutilated.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

In the drawings:

Fig. 1 is a top view of the ticket holder shown with a part of the closure and a guest ticket broken away.

Fig. 2 is a sectional view of the holder taken on line 2—2 of Fig. 1, shown clipped to a counter, or table.

Fig. 3 is an end view of the holder, shown with the holder closed.

Fig. 4 is a sectional view of the holder taken on line 4—4 of Fig. 1.

Fig. 5 is an illustration of the holder shown attached to a counter, or table.

In general

The invention is shown as applied for use in a restaurant, and for this reason guest tickets are illustrated in the holder. The holder is pro-

2

vided with a compartment having a resilient member for pressing one end of a pile of tickets therein against an inner ledge of the holder, so that the tickets are releasably held in the holder. A sliding closure is provided which is normally in closed position, and to obtain access to the top ticket of the pile, the closure is slid rearwardly, whereupon a finger can be inserted to buckle the rearward end of the top ticket to withdraw it from the holder. Thereafter the closure is moved forwardly beneath the removed end of the ticket to form a writing table for making entries on the ticket. After the guest has been served the ticket is removed by a slight pull. The rearward end of the holder is also provided with a non-movable table lying just beneath and in sliding contact with the closure to provide a hand rest for the waitress. The space beneath the hand rest provides a convenient space for insertion of a clip for clipping the holder to the counter so that the holder cannot be accidentally shifted, or moved, out of position. If desired the holder can be permanently secured to the counter by screws, or any other similar manner.

Detail description

The holder is provided with two side walls 10 and 11 which extend through the entire length of the holder. The side walls 10 and 11 are formed on a bottom plate 12, the forward end of which is formed upwardly to form an end wall 13, the latter being formed to provide a top ledge 14.

The side walls 10 and 11 have flanges 15 and 16, respectively, formed to extend outwardly therefrom at right angles thereto. A closure 17, is formed with U-shaped edges 18 and 19, to slidably engage the flanges 15 and 16 respectively. The closure 17 can thereby be moved forwardly to close the ticket compartment, and rearwardly from closed position to render the tickets in the compartment accessible. The closure 17 is long enough to close the compartment formed by a resilient member 20, formed to rest on the bottom 12, and which is formed on its rearward end to provide an upstanding wall 21. The forward part of the resilient member 20 is biased to engage and impinge the forward end of a pile of tickets 22 against the underside of the ledge 14 to releasably hold the pile of tickets in the holder. The rearward end of the holder is provided with a hand rest 23 having downwardly extending side walls 24 and 25. The hand rest extends from the rear end of the holder to a position a

short distance past the wall 21 of the member 20, the wall being wide enough to fit snugly between the walls 24 and 25.

The ledge 14 is resilient enough to permit the closure 17 to move therebeneath when moved to closed position. A slight depression 26 in flange 16 provides a stop to limit the movement of the closure 17. Thus, when the closure 17 is in closed position with a ticket resting thereon, the forward end of the ticket will be clamped between the underside of the ledge 14 and the top of closure 17, as illustrated in Fig. 3. Removal of the ticket from the pile will therefore not drag the next ticket from the top of the pile since at this time the pile is impinged against the underside of the closure 17.

As here illustrated, the holder is fastened to the top of a counter, or table 30. Any number of holders can be provided, one opposite each chair provided for serving a guest. It may be desired to provide for easy removal of the holder from the counter 30, for cleaning the counter top, or for any other purpose. One novel means for accomplishing this is to provide a clamp 31 made of spring material. The clamp 31 is provided with a leg 32 of sufficient width to fit snugly between the walls 24 and 25 of the hand rest 23. The plate 32 extends forwardly just short of the wall 21 of the resilient member 20. To aid in maintaining the holder firmly in position, the bottom 12 may be provided with a hole, or series of holes 33, and the plate may be provided with corresponding protuberances fitting the holes when the holder is in place. The clamp 31 is also provided with an upwardly extending leg 34, having a bent terminal 35 to bear on the underside of the counter or table 30. The member 31 being made of spring material firmly maintains the holder in position.

If it is desired to secure the holder more permanently to the counter top, screws 36 (Fig. 5) can be used, which screws are passed through the holes 33 above mentioned.

Operation

In its use the ticket holder is operated in the following manner. A holder is positioned opposite each guest chair provided in a restaurant. After the guest takes his seat, the waitress opens the closure 17 by sliding it rearwardly whereupon she inserts a finger into the opening and by buckling the top ticket, lifts the free end thereof out of the holder. She thereafter slides the closure back to its closed position where the forward end of the closure impinges the removed ticket between it and the underside of ledge 14. The closure 17 provides a writing table for making entries on the ticket. Writing on the ticket is facilitated by the hand rest 23 which lies rearward of the closure and the removed ticket. The waitress fills the order without removing the ticket from the table. When the guest is ready to leave, the waitress removes the ticket from the holder and presents it to the cashier for payment. One advantage of use of the invention is that the proprietor can have a complete check on the food served and charged by simply glancing at the ticket and noting the entries thereon. If a guest should be served without an entry on a ticket, this can be detected at once by the absence of a correct entry on an exposed ticket. Also the absence of an exposed ticket in the holder indicates to the proprietor that the guest has not been served.

An advantage of the invention is that the

tickets are always protected against becoming soiled and "dog-eared," since only the ticket to be written on is exposed. At all other times the pile of tickets are completely enclosed within the holder, and therefore, protected.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a device of the class described, the combination of a bottom plate adapted to be secured to a support, two side walls formed on said plate, an end wall formed on said plate, said side and end walls forming three sides of a rectangular compartment, a resilient member within the compartment and extending between said side walls, said resilient member being substantially shorter than the bottom plate, an upstanding wall formed on the resilient member extending from the bottom plate to a level with the tops of the side walls, and the forward end of the resilient member formed at an angle extending from the bottom plate upwardly toward the level of the tops of the side walls, and said resilient member being biased upwardly away from the bottom plate, a ledge formed on the end wall extending into the path of movement of the biased resilient member whereby the resilient member and the ledge form a clamping means to releasably hold a stack of tickets, a hand rest mounted on the bottom plate between the said side walls and the upstanding wall, and a closure movable to render the top ticket of said stack accessible so that one end thereof can be removed from the stack, said closure thereafter movable beneath the removed ticket to form a writing table for making entries on the removed ticket.

2. In a device of the class described, the combination of a bottom plate, means to secure the bottom plate to a support, two side walls formed on said plate, an end wall formed on said plate, said side and end walls forming three sides of a rectangular compartment, a resilient member within the compartment and extending between said side walls, said resilient member being substantially shorter than the bottom plate, an upstanding wall formed on the resilient member extending from the bottom plate to a level with the tops of the side walls, and the forward end of the resilient member formed at an angle extending from the bottom plate upwardly toward the level of the tops of the side walls, and said resilient member being biased upwardly away from the bottom plate, a ledge formed on the end wall extending into the path of movement of the biased resilient member whereby the resilient member and the ledge form a clamping means to releasably hold a stack of tickets, a hand rest mounted on the bottom plate between the said side walls and the upstanding wall, and a closure movable to render the top ticket of said stack accessible so that one end thereof can be removed from the stack, said closure thereafter movable beneath the removed ticket to form a writing table for making entries on the removed ticket.

3. In a device of the class described, the combination of a bottom plate, a resilient clamping means engaging the bottom plate and a support for the device to removably maintain the device

on said support, two side walls formed on said plate, an end wall formed on said plate, said side and end walls forming three sides of a rectangular compartment, a resilient member within the compartment and extending between said side walls, said resilient member being substantially shorter than the bottom plate, an upstanding wall formed on the resilient member extending from the bottom plate to a level with the tops of the side walls, and the forward end of the resilient member formed at an angle extending from the bottom plate upwardly toward the level of the tops of the side walls, and said resilient member being biased upwardly away from the bottom plate, a ledge formed on the end wall extending into the path of movement of the biased resilient member whereby the resilient member and the ledge form a clamping means to releasably hold a stack of tickets, a hand rest mounted on the bottom plate between the said side walls and the upstanding wall, and a closure movable to render the top ticket of said stack accessible so that one end thereof can be removed from the stack, said closure thereafter movable beneath the removed ticket to form a writing table for making entries on the removed ticket.

4. In a device of the class described, the combination of a bottom plate, two side walls formed on said plate, an end wall formed on said plate, said side and end walls forming three sides of a rectangular compartment, a ticket supporting member within the compartment and extending between said side walls, said ticket supporting member being substantially shorter than the bottom plate, an upstanding wall formed on the ticket supporting member extending from the bottom plate to a level with the tops of the side walls, a hand rest mounted on the bottom plate between said side walls and the upstanding wall, indentations on the upper surface of the bottom plate, a

40

resilient means having projections engageable with said indentations and a surface engageable with the underside of a support on which the bottom plate rests whereby the device is releasably held on the support.

5. In a device of the class described, the combination of a bottom plate, two side walls formed on said plate, an end wall formed on said plate, said side and end walls forming three sides of a rectangular compartment, a ticket supporting member within the compartment and extending between said side walls, said ticket supporting member being substantially shorter than the bottom plate, an upstanding wall formed on the ticket supporting member extending from the bottom plate to a level with the tops of the side walls, a hand rest mounted on the bottom plate between the said side walls and the upstanding wall, indentations on the upper surface of the bottom plate, a resilient clamp having one leg extending into the space beneath the hand rest and extending between the said side walls, projections on the said one leg engaging the indentations, said clamp having a second leg on the clamp, spaced from the first leg to provide means to hold the clamp and the device on a support.
